UNITED STATES PATENT OFFICE.

CHARLES E. CASTEEL AND WILLIAM B. FAIL, OF LITTLE RIVER, KANSAS,
ASSIGNORS OF ONE-HALF TO CHARLES E. HAMILTON, OF LITTLE RIVER,
KANSAS.

ADJUSTABLE RIDDLE FOR WINNOWERS.

SPECIFICATION forming part of Letters Patent No. 697,324, dated April 8, 1902.

Application filed March 6, 1901. Serial No. 50,102. (No model.)

To all whom it may concern:

Be it known that we, CHARLES E. CASTEEL and WILLIAM B. FAIL, citizens of the United States, residing at Little River, in the county 5 of Rice and State of Kansas, have invented a new and useful Adjustable Riddle for Winnowers, of which the following is a specification.

Our invention is an improved shaking-shoe 10 and adjustable riddle for threshing-machines, the object of our invention being to provide improved means for supporting the riddle in the shaking-shoe and for adjusting the riddle to any required inclination while the shaking- 15 shoe is in operation.

Our invention consists in the peculiar construction and combination of devices herein-after fully set forth and claimed.

In the accompanying drawings, Figure 1 is 20 a perspective view of a shaking-shoe and adjustable riddle constructed in accordance with our invention. Fig. 2 is a vertical longitudinal sectional view of the same. Fig. 3 is a detail side elevation of the same. Fig. 25 4 is a diagrammatic longitudinal sectional view of a threshing-machine, showing the same provided with our improved shaking-shoe and adjustable riddle.

The shaking-shoe 1 is of the usual form or 30 may be made of any desired form and is suspended in the threshing-machine and vibrated longitudinally therein by the usual means, which are well known to those skilled in this art and form no part of our present 35 improvements.

A supporting and adjusting shaft 2 is disposed transversely across the shoe, has its bearings in the sides thereof and at one end projects beyond one side of the shoe, and is 40 provided with a worm wheel or segment 3, the same being fast on the said shaft. That portion of the shaft 2 which is between the sides of the shoe is angular, as shown, and the said shaft supports a pair of bars 4, which 45 are longitudinally disposed in the shoe and are of suitable length. Clips 5, which embrace the lower side of the shaft 2, are connected to the under sides of the bars 4, and thereby the latter are firmly secured on the 50 shaft 2, and are adapted to be adjusted

thereon longitudinally of said shaft to enable the bars to be moved toward or from each other, as may be required to adapt them to engage the sides of screens or riddles which may vary in width. As here shown, the bars 55 4 are provided on their outer sides with flanges 6 and at their ends with flanges 7, said flanges 6 and 7 bearing against the sides and ends of the frame of the screen or riddle, and hence maintaining the latter on the said bars. This 60 construction of the said bars enables the screen or riddle to be readily placed thereon or removed therefrom, and it will be understood that said bars support the said screen or riddle in the shoe, and as the said bars are sup- 65 ported by the shaft 2 it follows that the inclination of the screen or riddle may be varied as may be required by partly turning said shaft 2 and securing the same when the screen or riddle is disposed at the desired in- 70 clination.

A longitudinally-disposed adjusting-shaft 8 is journaled in suitable bearings 9 on one side of the shoe. The rear end of the said adjusting-shaft projects beyond the rear end of said 75 shoe, and said adjusting-shaft is provided at its rear end with a suitable handle 10, by means of which it may be readily grasped and rotated manually. At the front end of the said adjusting-shaft 8 is a worm 11. The latter engages the worm wheel or segment 3, and hence when the said adjusting-shaft 8 is turned power is communicated to the shaft 2, and the latter is partly turned in its bearings and caused to adjust the screen or riddle, as 80 85 will be understood.

It will be understood from the foregoing that the screen or riddle may be adjusted in the shaking-shoe while the machine is in operation and while the shaking-shoe is being vi- 90 brated.

Having thus described our invention, we claim—

A shaking-shoe having a shaft 2 journaled therein, a worm-wheel on said shaft, a set-shaft 95 having a worm engaging said worm-wheel, supporting-bars attached to, and supported solely by said shaft 2, said bars having side flanges 6 and end flanges 7 on their upper sides, and a removable screen or riddle supported 100

on said adjustable bars, adapted to be lifted therefrom and engaged by the flanges thereof, said bars being laterally adjustable on said shaft to adapt them to receive and support 5 riddles or screens of various widths, substantially as described.

In testimony that we claim the foregoing as

our own we have hereto affixed our signatures in the presence of two witnesses.

CHARLES E. CASTEEL.
WILLIAM B. FAIL.
